UNITED STATES PATENT OFFICE.

PHILIP FITZSIMONS, OF BIRMINGHAM, ALABAMA, ASSIGNOR OF ONE-HALF
TO FREDERICK HARDY, OF SAME PLACE.

TELEPHONE-TRANSMITTER.

SPECIFICATION forming part of Letters Patent No. 453,581, dated June 2, 1891.

Application filed September 9, 1890. Serial No. 364,396. (No model.)

To all whom it may concern:

Be it known that I, PHILIP FITZSIMONS, a citizen of the United States, residing at Birmingham, in the county of Jefferson and State 5 of Alabama, have invented certain new and useful Improvements in Telephone-Transmitters; and I do hereby declare the following to be a full, clear, and exact description of the invention, such as will enable others skilled 10 in the art to which it appertains to make and use the same.

My invention relates to telephone-transmitters and aims to reduce the number of the parts, to diminish the battery force required 15 and increase the durability and add to the usefulness of this class of instruments.

The improvement consists of the novel features which will be hereinafter more fully described and claimed, and which are shown in 20 the annexed drawings, in which—

Figure 1 is a diagrammatical view of a telephone-transmitter embodying my invention, showing the direction of circuits. Fig. 2 is a modified form of electrodes to be attached to 25 the diaphragm. Fig. 3 is a perspective view of the receiver-supporting hook. Fig. 4 is a detail perspective view of the central post which supports the carbon electrodes, showing it provided with a slot by means of which 30 the electrodes can be replaced.

The parts are suitably incased and comprise the diaphragm A, as shown in the accompanying drawings, of wood, Spanish cedar being preferred because of its non-conducting 35 combined with vibratory qualities. This diaphragm is stretched over a rigid frame A', and is securely fastened thereto in such a manner that it will at all times be held under tension both longitudinally and laterally.

40 By having the diaphragm held under tension its resonance is increased and it is not affected by dampness. The preferable way of mounting the diaphragm is first to wet it, thereby expanding it to its fullest capacity, and then 45 stretch it over and secure it to the frame. The carbon posts R R and T are supported on or secured to the diaphragm and have the ends of the carbon electrodes S S, which are placed between them, inserted in the sides 50 thereof. Instead of three posts, as shown in Fig. 1—a central and two end posts—and hav-

ing the carbon electrodes one on each side of the central post, two posts R' R' may be provided having the carbon electrodes supported between them, as shown in Fig. 2. 55 The posts R R are connected together and with binding-posts P P by wires Q Q.

The hook or shunt-lever C, on the outer forked end of which the receiver is supported, is made of a non-conducting material, such 60 as vulcanized rubber, celluloid, papier-maché, wood, or like material. The pin D, passing transversely through the end of the lever and projecting above and below the same for some distance, is electrically connected with the 65 fulcrum B by the metal strip c. The conducting-wire a³ connects the metal or conducting fulcrum B with the push-button or switch B².

The induction-coil f has the terminals O O of the primary wire connected with the binding-posts P P and the post N, respectively, 70 the secondary wires F and F³ being connected with the posts G and E, respectively. The spring-arm m, attached to the plate M, to which the wires L and C² are connected, is 75 adapted to bear on the post N and projects within the path of the inner end of the hook or lever C. The wire C² extends to the push-button or switch B² and the wire L connects with the binding-post k. The post D² directly 80 above the post E is connected by wire j with the binding-post J', to which one wire from the bell J² is attached, the other wire from the bell being connected with the binding-post J, which is grounded through wire j'. 85 The wire a², extending from the switch or push-button B², has connection with the binding-post a, to which the line-wire is attached. The battery M' has its poles in electrical connection with the binding-posts K and k. 90

The operation of the invention is as follows: The battery-current passes from the binding-post k by the wire L to the plate M and spring m, thence through the binding-post N and wires O O of the primary circuit 95 of the induction-coil to the binding-posts P P, thence by the wire Q Q to the carbon posts R R, supporting the outside ends of the electrodes S S, through these electrodes to the central carbon post T and the wire X to the binding-posts V V, thence to the binding-post K, completing the battery-circuit. The in- 100

duced current-circuit is through the secondary circuit of the induction-coil by the wire F^3 to the binding-post E , through the pin D , plate c , fulcrum B , wire a^3 , push-button B^2 , and wire a^2 to the binding-post a , to which the line-wire is attached, back through ground to binding-post J and wire I to binding-post H , by double wire cord E^2 to receiver F^2 , and back to binding-post G , completing the circuit through wire F . The push-button B^2 is a three-point switch, through which the line-wire a^2 passes from the binding-post a to the fulcrum B , except when the button is pressed, when the current from the binding-post k is sent through the wires L , C^2 , and a^2 out over the line, ringing the bell at the other end, the current being grounded through wire k^2 , binding-post K , and wire j^2 . When the receiver is placed on the hook, the spring m is detached 20 from the binding-post N , breaking the primary or battery circuit. The pin D then being in contact with the binding-post D^2 , the current received over the line would pass from the binding-post D^2 through the bell 25 to ground at J . The vibration of the diaphragm causes a variation of the current in the primary circuit by causing a variation of pressure between the electrodes and the supporting-posts, in which the holes are sufficiently large to allow free play of the electrodes. This produces a corresponding variation 30 in the induced current of the secondary circuit, which variation is transmitted over the line. One cell is sufficient to operate the 35 telephone above described, whereas other car-

bon telephones having a greater number of electrodes require greater battery-power. To facilitate the removal and the replacement of the electrodes S S , the central support T is provided in its side with a slot through which the reduced ends of the electrodes are passed when removing or replacing the said electrodes.

In Fig. 2 the electrodes S S are arranged in parallel position and supported at their ends in posts R' R' , which are in electrical connection with the binding-posts P P and V V by means of the wires Q' Q' .

Having thus described my invention, what I claim, and desire to secure by Letters Patent, is—

In a telephone-transmitter, the combination of the posts D^2 , N , and E , forming terminals of the bell-circuit, primary and secondary wires of the induction-coil, respectively, the plate M , forming terminal of the battery and having spring m , which is adapted to make electrical connection with the post N and the hook C , of non-conducting material, having metal conductor c , and the transverse pin D , the end projecting within the path of the spring m , substantially as and for the purpose described.

In testimony whereof I affix my signature in presence of two witnesses.

PHILIP FITZSIMONS.
